Attest:

UNITED STATES PATENT OFFICE.

WILLIAM H. VOSS, OF DAVENPORT, IOWA.

WRINGER.

1,196,317.

Specification of Letters Patent. Patented Aug. 29, 1916.

Application filed October 14, 1915. Serial No. 55,799.

To all whom it may concern:

Be it known that I, WILLIAM H. Voss, a citizen of the United States, residing at Davenport, in the county of Scott and State 5 of Iowa, have invented certain new and useful Improvements in Wringers, of which the following is the specification.

This invention relates to a safety device for wringers, and particularly to a device 10 whereby the wringer rolls may be instantaneously released in case of emergency.

It is an object of the invention to provide a simple, and economical safety attachment of the character described, which may 15 be applied with only slight modification of parts on existing wringers, and in which the safety handle is located in a conspicuous and easily accessible position.

It is another object of the invention to 20 provide a safety attachment of the character described which cannot get out of order and is simple of construction and easy of operation.

It is another object of the invention to 25 provide a safety attachment of the kind described, wherein the safety device requires modification only of the cross bar and connecting standards of an all metal wringer.

Other objects and advantages of the in- 30 vention will appear as the description to follow proceeds.

In the drawings: Figure 1 is a front elevation of my device, certain parts being shown in full and dotted line position. Fig. 35 2 is a sectional view thereof on the line II—II of Fig. 1. Fig. 3 is a detail cross sectional view on the line III—III of Fig. 1. Fig. 4 is a sectional and detail view of the mechanism upon one of the wringer 40 standards.

1 represents in general the lower half of a wringer designed to be attached to a support by slotted ears 2 and provided with sockets 3 to accommodate the ball races for 45 the journals of the lower wringer roll. Rigidly mounted in the frame 1 are upright standards 4, one at either side. These standards are screw-threaded at their upper ends 5. The upper wringer rolls are 50 carried in arms 6 and provided with pins 7 which take into recesses in the rearwardly extending arms 8 upon the frame 1, and are further provided with apertures through which the standards 4 project upwardly. 55 Sleeved upon the standards 4 are coil springs 9 bearing at their lower ends

against the arm 6 to create tension between the wringer rolls. A cross bar 10 with enlarged ends 11 in which are swiveled thumb-screws 12 connects the upper ends of the standards and may be adjusted vertically by means of the thumb-screws. The cross bar 10 is, according to my invention, provided with depending T-flanges 13 adjacent either end, upon which are slidably mounted the blocks 14 which are slotted vertically and provided at their upper ends with curved bearing surfaces 15 to take against the bottom of the cross pieces 10 and at their bottoms with feet 16 which engage with the upper ends of the coil springs 9, the blocks 14 being slotted, as shown, so that they may move into a position vertically above the coil springs 9 without interfering with the standards 4. The cross 75 piece 10 is provided with a vertical slot 16 at its center and with substantially semi-circular webs 17 to provide a protecting chamber for the safety release operating mechanism. Pivotedly mounted upon a bolt 18 and spanning the web 17 is a lever 19. Pivotedly connected to it upon opposite sides of its pivotal pin are links 20 which at their outer ends are formed integrally with the blocks 14. 85

The sleeve 21 surrounds each standard 4 in order to render more easy the operation of the springs and to confine them against getting too far out of line with respect to the feet 16 of the blocks 14. This element, 90 however, could be dispensed with.

In operation, the cross piece 10 is raised by means of a thumb-screw 12 until the blocks 14 are above the upper ends of the springs 9 when these springs are expanded. 95 The handle 19 is then operated from the blocks 14 outwardly and causes them to assume a position directly between the outer ends of the cross bar 10 and the upper ends of the springs 9, whereupon the thumb-screws 12 are operated to force the cross bar 10 downwardly and supply whatever tension may be desired to the wringer rolls. In case of emergency, such as a catching of the fingers of the operator between the 105 wringer rolls, it will only be necessary to give the lever 19 a sharp push to move it from the position shown in dotted lines in Fig. 1. This action will instantly retract both blocks 14 and release the tension upon the wringer rolls. To reset the mechanism the cross bar 10 may be raised and the blocks 110

again moved outwardly, as above described. The large leverage obtained upon the blocks 14 in combination with the wide arc described by the points of connection between 5 the links 20 and the lever 19, makes the release both instantaneous and easy. The fact that the thumb screws 12 are permanently swiveled in the cross bar prevents the parts from flying apart when the tension is released.

Having now described my invention, I claim:

1. In a wringer, a pair of rolls, a pair of standards operatively associated with the 15 rolls, tension means, comprising coil springs bearing on the upper roll and mounted upon said standards, a cross piece connecting said standards at their upper ends and adapted to be moved downwardly thereon, a pair of 20 blocks slidably mounted in said cross piece and adapted to be interposed between said cross piece and the upper end of said coil springs, and means for simultaneously and 25 instantaneously withdrawing said blocks to release the wringer rolls.
2. In a wringer, a pair of standards, a pair of rolls associated therewith, tension means arranged adjacent each standard, a cross piece adjustably mounted upon said standards and release means on said cross piece and adapted to be interposed between the same and the tension means and to be instantly released.
3. In a wringer, a frame, a pair of standards thereon, rolls, tension means associated with said standards, a cross bar connecting the upper ends of said standards and vertically adjustable on said standards, and in-

stantaneously releasable means interposed between said cross bar and said tension 40 means.

4. In a wringer, a pair of standards, a cross piece adjustably connected thereto, blocks having recesses for the accommodation of said standards and slidably mounted on said cross bar, a lever centrally mounted on said cross bar and connections from said lever to said blocks for longitudinally moving them.

5. In a wringer, a pair of standards screw-threaded at their upper ends, a cross bar having thumb nuts swiveled thereon at either end and in engagement with said threads, a wringer release device mounted on said cross bar and comprising instantaneously releasable means interposed between the same and the wringer rolls.

6. In apparatus of the class described, rolls, tension means associated therewith, a pair of standards, a cross bar connecting said standards, an enlarged chamber located substantially centrally of said cross bar, tension release means, and a control for said tension release means, comprising a lever pivoted in said chamber and links pivotally connected to said lever at points a substantial distance upon opposite sides of the pivotal point of said lever.

In witness whereof, I hereunto subscribe my name to this specification in the presence 70 of two witnesses.

WILLIAM H. VOSS.
